ACTION TOY

Walter P. Doe, Leslie W. Sly, and Herman G. Fisher, East Aurora, N. Y., assignors to Fisher-Price Toys, Inc., East Aurora, N. Y.

Application March 6, 1948, Serial No. 13,397

1 Claim. (Cl. 46—119)

1
This invention relates to action toys, and more particularly to improvements in mass-produced and relatively inexpensive toy moving parts and actuating mechanisms therefor.

One of the objects of the invention is to provide an improved action toy of the type having flexing body-simulating elements, and novel means for actuating such elements to provide improved simulation of animal-like actions.

Another object of the invention is to provide an improved toy embodying the features aforesaid, wherein the operative elements are also of improved structural simplicity and ruggedness.

Another object of the invention is to provide an improved toy of the character aforesaid which is relatively inexpensive to manufacture and fabricate.

Other objects and advantages of the invention will appear in the specification hereinafter.

In the drawing:

Fig. 1 is a side elevation of a toy embodying the invention;

Fig. 2 is a top plan thereof; and

Fig. 3 is a fragmentary front elevation thereof.

The drawing illustrates the invention for example, as being embodied in an action toy simulating an animal of the elephant type, but it is to be understood that the invention is applicable with equal facility to toys having flexible moving parts simulating any other figures. Thus, the drawing illustrates the toy to comprise a body portion 10 which may be inexpensively fashioned by jig-saw cutting wood or plastic or metal or any other suitable material to simulate the major body portion of the depicted figure; and in this instance the body 10 is formed with legs 12. Axes 14 are journaled in the bottom ends of the legs to extend transversely between the paired front and rear legs, respectively; and wheels or rollers 15 mount upon the axes 14 so that the toy is thereby arranged to be pulled or pushed along any suitable supporting surface.

One of the axes 14 is formed with a crank portion 16 which is engaged by the lower end of a connecting rod 18. The rod 18 extends upwardly through a suitably apertured portion 19 of the body block 10, and connects at its upper end upon a cantilever arm 20 which is fixed to extend laterally from a rocker shaft 22 which is journaled at its opposite ends in the body block 10. The shaft 22 is arranged to extend longitudinally of the toy and beyond the front and rear end portions of the toy body. A tail piece 24 is fixed to the rear end of the shaft 22 and a head piece 25 is fixed to the extending front end

of the shaft. To enhance the natural appearance of the body parts, the head and tail pieces 24—25 are cut to smaller width dimensions than the body 10, when seen in plan view. Thus, it will be understood that upon rolling movement of the toy the traction wheels 15 will drive the crank shaft 16 so as to operate the connecting rod to cause the rocker shaft 22 to oscillate in its bearings. Thus, the head and tail portions 10 25—24 of the toy are caused to swing back and forth about the axis of the shaft 22, thereby simulating head and tail swinging movements of the depicted animal.

To further improve the appearance of the toy 15 and to provide further animal-like movements of the figure depicted, it is a feature of the present invention that the shoulders 26—26 at the juncture of the body and head portions be covered by movable flexible elements. Thus, as shown in 20 the drawing flexible fabric flaps 30—30 may be fixed to the head member, as by means of tacks 32, to overlie the shoulders 26—26; and preferably the members 30 are shaped to simulate some naturally flexing member of the animal being depicted. Thus, in the case of the present drawing the members 30 are formed to simulate the flapping ears of an elephant, but it will be understood that the flexing members may in the case of other toy forms be shaped to simulate other animal parts such as wings, legs, feet, arms, ears, or any other physical features.

In any case, in accord with the present invention, a flexible flap device as at 30 will be fixed to one of the relatively moving body portions in 35 such manner as to overlie the juncture therebetween and to resiliently bear against the other body member so that as the actuating mechanism operates to oscillate one of the body members relative to the other the resilient flap member 40 will be thereby elastically deformed and motivated so as to be given a novel twisting and flapping movement. For example, in the elephant type toy depicted in the drawing, the ear members 30—30 are fixed to the head 25 in such manner as to extend rearwardly therefrom in resilient cantilever fashion, thereby bearing against the shoulder portions 26—26 of the body 10, as shown in Fig. 2. However, upon twisting 45 of the shaft 22 upon its axis, the head 25 is caused to oscillate as explained hereinabove, whereby different portions of the ear flaps 30—30 are brought to bear against the shoulders 26—26, thereby imparting to the flaps 30 peculiar twisting and flapping movements which realistically 50 55

imitate the multi-form flapping and flexing movements of the ears of a live elephant.

It is also a particular feature of the present invention that the above recited novel flexing action is obtained in combination with a particularly important improvement in the structural form of the animal toy. This is because by reason of the invention the body block 10 may be economically produced in accord with quantity production methods in simple jig-saw cut square corner block form, to embody properly proportioned width-to-length dimensions, while the head member 25 may be similarly jig-saw cut from boards of suitable thickness so as to provide a properly proportioned head; while the resilient flap members 30-30 act to give the finished toy an overall streamlined appearance because of the fact that they overlie the shoulder corner portions 26-26 of the body block. Thus, the flaps 30-30 not only function with an improved flexing ear flapping simulating motion, but also cover the otherwise unrealistic appearing sharp shoulder corner portions 26-26 of the block 10, and streamline the juncture between the head piece and the body block; thereby providing a relatively inexpensively manufactured toy having an improved action and overall appearance.

As explained hereinabove, the flexible flap elements of the toy of the invention may assume any required shape or form such as to imitate some limb or other extending feature portion of the figure depicted in the toy, according to the style of the toy; and in any case the flexible elements will be actuated in the manner of the present invention by means of a suitably arranged adjacent oscillating portion of the toy.

Therefore, it will be understood that although only one form of the invention has been shown and described in detail it will be apparent to those skilled in the art that the invention is not so limited but that various changes may be made therein without departing from the spirit of the invention or the scope of the appended claim.

What is claimed is:

10 In an action toy, a body member having an end wall portion, an accessory member mounted upon said body to oscillate thereon about an axis directed substantially normal to said end wall, means to cause said accessory member to oscillate relative to said body member, and a flexible flap member simulating a feature of the figure depicted by the toy, said flap member being fixed to one of said members so as to overlie the juncture between said body member and said accessory member while bearing against said body 15 end wall portion, whereby upon oscillation of said accessory member said flap member is displaced by the changing relationship of said body and flap member and caused to twist and flap.
